Joshua Gordon Lippincott, Scarsdale, N. Y., assignor to D. Ornstein & Sons, New York, N. Y.

Application June 15, 1945, Serial No. 120,125

Term of patent 7 years

(Cl. D80—5)

To all whom it may concern:

Be it known that I, Joshua Gordon Lippincott, a citizen of the United States, residing at 5 Reynal Crossing, Scarsdale, Westchester County, New York, have invented a new, original, and ornamental Design for a Jewelry Case, of which the following is a specification, reference being had to the accompanying drawing, forming part thereof.

In the drawing, the figure is a perspective view of a jewelry case showing my new design.

I claim:

The ornamental design for a jewelry case, as shown.

JOSHUA GORDON LIPPINCOTT.
